UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SEPARABLE ATTACHMENT-PLUG.

1,103,250.

Specification of Letters Patent. Patented July 14, 1914.

Application filed August 10, 1909. Serial No. 512,147.

To all whom it may concern:

Be it known that I, REUBEN B. BENJAMIN, a citizen of the United States, residing at Chicago, in the county of Cook and State 5 of Illinois, have invented new and useful Improvements in Separable Attachment-Plugs, of which the following is a full, clear, concise and exact description, reference being had to the accompanying drawing, forming 10 a part of this specification.

This invention relates to improvements in separable attachment plugs, the object of the invention being to provide a device in which the part which makes connection directly 15 with the stationary socket may be readily separated, when desired, from the part which carries the binding terminals to which are secured the leading-out conductors, the device being so constructed, 20 however, that accidental separation is not likely to occur unless an abnormal strain be placed upon the conductors, when the parts may separate in order to prevent damage being done to the device or the stationary 25 socket, or the wires being torn loose from the binding terminals of the device.

Another object of the invention is to provide a device of this class which is so constructed that when it is desired to 30 finally separate the two parts thereof without jarring the fixture which carries the socket with which connection is made this may be done by giving a slight rotation to the part which is grasped by the hand, this being the 35 part which carries the binding screws and wires.

Heretofore, as separable attachment plugs have usually been constructed, the separation of the parts has been effected by simply 40 withdrawing one of the parts from the other with a straight pull. This has proven to be objectionable in many instances as where the socket with which connection is made forms part of a chandelier carrying a number of 45 lamps and shades therefor. When a direct pull is exerted to separate the parts the separation is resisted for a time until the force exerted becomes great enough to overcome the resistance of the clips or other 50 parts which tend to hold the members of the plug together, whereupon these members separate with a sudden jerk which is liable to cause damage to the chandelier, shades and the like. By the use of my invention 55 this difficulty is overcome, it being possible

to separate one part of the plug from the other without any undue force being employed or vibration caused.

In the accomplishment of the above objects I provide a cap member which is arranged to be screwed into the stationary socket, which cap member carries a side contact and an end contact arranged for engagement with the corresponding contacts of the socket. I then provide a plug member from 60 which extend the leading-out wires, said plug member being arranged to be inserted into the cap member and, when so inserted, to make electrical connection between certain contacts carried thereby and the contacts of said cap member, the contacts of the plug being electrically connected with the binding terminals to which the wires are secured. Electrical connection is thus made 65 between the wires and the contacts of the stationary socket. I also provide means 70 whereby an abnormal strain exerted in a direction which would tend to cause the plug member to pull out of the cap member will not be resisted to such an extent as to prevent 75 such separation, although any such strain as would ordinarily be placed upon the device will be insufficient to cause the parts to separate. The interlocking parts upon 80 the two separable members are arranged to 85 make connection when one of said members is thrust directly into the other. After the parts have thus become locked together sufficient resistance to the separation of said 90 parts is offered to prevent the same from separating under ordinary conditions, as above stated, but if a slight rotation is given to the plug member relatively to the cap member, said parts automatically unlock, the plug member being forced out of the cap 95 member to some extent, thus insuring the parts remaining detached from each other.

In the accompanying drawings, Figure 1 is a side elevational view of the device with the two separable members put together; Fig. 2 is a bottom plan view of the upper or cap member, or that member which is arranged 100 to be inserted into a socket; Fig. 3 is a top plan view of the lower or plug member; Fig. 4 is a bottom plan view of the plug 105 member, the insulating cap which incloses the lower part of the same being removed; Fig. 5 is a longitudinal sectional view of the device with the separable members connected to each other; Fig. 6 illustrates the device 11

with the members separated, the cap member being shown in section on the line 6—6 of Fig. 2, looking in the direction of the arrows; while the plug member is shown in 5 elevation; Fig. 7 is a sectional view of the upper portion of the plug member, the section being taken on the line 7—7 of Fig. 4, looking in the direction of the arrows; and Fig. 8 is a sectional view of a portion of the 10 plug member, the section being taken on the line 8—8 of Fig. 4, looking in the direction of the arrows.

In the several figures of the drawings, 10 is an insulating base member which occupies the upper portion and extends somewhat beyond the upper end of a threaded metallic ring 11. Below the threaded part of the ring the same is drawn in slightly at 12, the base 10 resting upon the shoulder 20 formed by thus drawing in the material of the ring, and being further held in place by the indented semicircular bosses 12^a on the ring. To hold the base against upward movement in the ring the base is formed 25 with a pair of oppositely disposed cavities 13, the material of the ring at its upper edge being turned over into these recesses at 14. Surrounding the lower portion of the ring is an insulating sleeve 15, the latter being 30 prevented from slipping off the lower end of the threaded ring by forming the ring with a bead 16 at its lower edge and bead- 35 ing the insulating sleeve at 17 so that the bead on the ring occupies the bead in the sleeve.

The lower portion of the insulating base is chambered out at 18. From this chamber a passage extends upward through the base and opens at the upper end of the latter. 40 A contact member comprising a strip 19, which extends across the upper end of the chamber in the base and is provided with a downwardly extending leg 20 at each of its ends, is secured in position in the chamber by means of a hollow rivet 21 which extends through the aperture of the base and is headed over at its upper end to form a center contact member for the device. When the cap member, which comprises the base 45 and threaded ring, is screwed into a socket electrical connection is made by the threaded ring with the threaded contact of the socket and by the contact member 21 with the center contact of the socket.

50 The lower or plug member comprises an insulating base 21^a made somewhat cone-shaped and having a metallic ring 22 extending around its lower and larger portion, this ring being turned over inward upon a shoulder 23 formed upon the base. The lower end of the ring 22 is drawn in under the base 21^a and then extends downward to form a neck 24 having screw threads 55 rolled in the material thereof. A cap 25, 60 which incloses the threaded part 24 of the

ring 22, is formed of insulating material and has a neck portion 26 which is exteriorly screw threaded and screws up into the neck 24. Between the upper edge of the cap 25 and the shoulder caused by drawing in the 70 material of the ring 22 under the base is arranged an insulating ring 27 which extends laterally beyond the edge of the cap so as to be readily grasped by the fingers of a person. Upon the lower end of the base 75 there is formed a projecting hump 28 which extends down for a short distance into the neck 26 of the insulating cap 25. When the leading-out conductors are in position and the cap 25 is screwed up in place the 80 conductors are gripped between the inner wall of the upper end of the neck 26 and this hump 28, whereby the conductors are securely held and undue strain, which might otherwise be exerted upon the binding 85 screws to tear the conductors from the same, is avoided.

When the base 21^a and the ring 22 carried thereby, which form the insertible part of the device, are thrust into the lower end of the cap portion of the device electrical connection is made between the interior of the ring 11 and the exterior of the ring 22. To insure good electrical contact being made the ring 11 is provided with three inwardly 90 projecting humps 30 which make rubbing contact with the ring 22. A binding screw 31 is provided for making electrical connection of one of the leading-out conductors with the ring 22, this binding screw being 95 carried by a tongue 32 formed by cutting the ring 22 vertically at each side of the screw 31, the tongue being set back into a suitable recess formed in the base 21^a. The screw 31 is provided with a nut 33 located in the 100 recess in the base, being prevented from rotating by the shape of the recess. A passage 105 34 extends from the under side of the base up to the tongue 32, this passage being provided for the accommodation of the lead wire, which will extend therethrough and emerge at the left hand edge of the tongue 32 in position for attachment to the binding screw 31.

A chamber 35 extends down into the base 110 21^a from the upper end of the latter. From this chamber a passage 36 extends downward and opens at the bottom of the base. The upper portion of the chamber 35 is enlarged in diameter to receive a cup-shaped 115 contact piece 37. The contact piece 37 is held in position by a plate 38 which is provided with a pair of prongs 39, the latter being bent downward at a right angle with the body of the plate and extending through 120 openings or passages which lead down from the chamber 35. The lower ends 40 of these prongs are turned outward and extend laterally into channels 41 in the under side of the base. A binding screw 38^a screws into the 125 130

plate 38 and has its head sunk in the cup-shaped contact piece 37. An opening 37^a is made in the contact piece 37 for the passage of the second wire to the binding screw 38^a after the same has been brought up through the passage 36. The cup-shaped contact piece 37 has its side walls bowed outward intermediate its top and bottom, thus becoming an enlarged head which, when the lower or plug portion of the device is inserted into the upper or cap portion thereof, is gripped upon opposite sides by the resilient fingers 20 of the contact piece 19 carried by the cap portion. The lower ends of the contact fingers 20 are inclined inward and then outward so that when the parts are thrust together the contact fingers will be wedged apart to permit the head 37 to pass therebetween. The inwardly projecting heels 42 upon the contact fingers grip under the head 37 when the parts are put together, and thus hold the plug portion of the device locked to the cap portion.

The upper end of the base 21^a of the plug portion is made wedge-shaped, being tapered off at each side of a line extending across the axis, as clearly seen in Figs. 3, 5 and 6. When the parts are thrust together, as illustrated in Fig. 5, the lower, outwardly inclined portions of the contact fingers 20 rest upon the inclined sides 43 of the base 21 but are not prevented from firmly gripping the head 37. If, however, a slight rotation be given to the plug portion of the device, the inclined lower ends of the spring fingers are caused to ride up the inclines and are compelled to open. When the plug portion has been revolved far enough to carry the contact fingers nearly up to the highest points of the inclines the fingers are opened sufficiently to release the head from their grasp, permitting the plug portion of the device to drop out of the cap portion.

By the arrangement of a head upon the lower portion and resilient fingers upon the upper portion arranged to grip under this head, there is afforded a form of lock which is impositive, and which thus permits the device to be separated when an undue pulling strain is exerted upon the parts, this lock being, however, sufficiently positive in its action to give all needed security against separation under normal conditions. By the provision of the wedge-shaped portion upon the upper end of the plug adjacent the head means are provided whereby a slight rotation (at most a movement equal to one-fourth of a complete revolution) of one part within the other unlocks the device. Very little effort is required in revolving the plug member to separate the members, thus but little twisting effect is imparted to the upper portion of the device. When the parts are brought to the proper angular relation to each other the plug portion is automatically

thrust out by the resilient fingers, thus not only is no direct pull upon the plug required when the device is to be manually separated, but it is rendered impossible to give such a pull to the device if the plug is turned to the unlocking position. It will thus be seen that in unlocking one part from the other the action is exceedingly smooth, there being complete freedom from the sudden breaking away of one part from the other, with the consequent tendency to a reaction, which is common to other separable attachment plugs, and which reaction results in damage to fixtures, shades and the like.

Having thus described my invention, what I claim as new and desire to secure by Letters Patent, is:

1. An attachment plug comprising two separable members, one of said members having contacts for coöperation with the contacts of a socket, and the other member having binding terminals associated therewith; means for locking said members together with said contacts in electrical communication with said binding terminals, said locking means being releasable upon the application of a predetermined force to said binding-terminal-carrying-member in a direct pull, and manually operable means for releasing said locking means and at the same time forcing said members apart.

2. An attachment plug comprising two separable members, one of said members having contacts for coöperation with the contacts of a socket, and the other member having binding terminals associated therewith; means for locking said members together with said contacts in electrical communication with said binding terminals, said locking means being releasable upon the application of a predetermined force to said binding-terminal-carrying-member in a direct pull; and means for releasing said locking means and at the same time forcing said members apart, upon rotation of one of said members with respect to the other.

3. In an attachment plug, the combination of a pair of separable members, one of said members having contacts for coöperation with the contacts of a socket, binding terminals carried by the other of said members, means for locking said members together with said contacts and binding terminals in electrical communication with each other upon a direct thrust of one of said members toward the other, said locking means being releasable upon the application of a predetermined force to said binding-terminal-carrying-member in a direct pull, and means for releasing said locking means upon rotation of one of said members with respect to the other.

4. An attachment plug comprising two separable members, one of said members being provided with a center contact and an

- outer contact for engaging the center contact and the threaded contact respectively of a socket, and the other of said members having binding terminals associated therewith, 5 a spring clip carried by one of said members, a clip-engaging member carried by the other member, and means upon said last-named member for releasing said spring clip upon said last-named member being rotated.
- 10 5. An attachment plug comprising two separable members, one of said members being provided with a center contact and an outer contact for engaging the center contact and the threaded contact respectively 15 of a socket, and the other of said members having binding terminals associated therewith, said second-named member being formed with a cam surface; a contact head carried by said second-named member and 20 electrically connected with one of the binding terminals thereof; and a spring clip carried by said first-named member and adapted to receive said head when said members are thrust together, said clip being electrically connected with one of the contacts of 25 said first-named member, and said clip being arranged to be engaged by the cam surface of said second-named member and opened thereby upon said second-named member 30 being rotated.
6. In a separable attachment plug, the combination of a pair of telescoping members, external contacts carried by one of said members, binding terminals carried by 35 the other of said members and arranged to be brought into electrical connection with said external contacts when said members are thrust together, one of said members having an incline formed thereon, a head 40 extending beyond said incline, and resilient fingers carried by the other member and

arranged to grip said head, said fingers riding upon said incline when the parts are received with respect to each other and being thereby forced out of engagement with said head. 45

7. A separable attachment plug comprising a pair of telescoping members, one of said members being provided with a center contact and an outer contact for engaging the center contact and the threaded contact respectively of a socket, and the other of said members having binding terminals associated therewith, said second-named member having an incline formed thereon; a contact head carried by said second-named member and electrically connected with one of the binding terminals thereof; and resilient fingers carried by said first-named member and electrically connected with one of the contacts thereof, said fingers being arranged to ride upon said incline when said second-named member is rotated and to be thereby forced out of engagement with said head. 55 65

8. An attachment plug comprising an insulating block having a depression in the side thereof, a center contact associated with said block, an outer contact-sleeve surrounding said block, said sleeve having a portion thereof indented into the recess of said block, and a binding screw associated with said contact-sleeve at the indented portion thereof. 70 75

In witness whereof, I have hereunto subscribed my name in the presence of two witnesses.
